TRAY OR THE LIKE

Jerome Lewis, 230 5th Ave., New York, N.Y.

Filed Oct. 17, 1963, Ser. No. 77,014

Term of patent 14 years

(Cl. D44—10)

FIG. 1 is a top plan view of a tray showing my new design;

FIG. 2 is a bottom plan view thereof;

FIG. 3 is a side elevational view thereof;

FIG. 4 is an end elevational view thereof; and

FIG. 5 is a longitudinal sectional view of the tray.

The characteristic feature of the design resides in the combination of a peripheral wall of constant thickness having smooth outer walls, ribbed inner walls and a narrow lip portion with a smooth-topped tray of the form disclosed having a raised circular well adjacent one end thereof, all as shown.

I claim:

The ornamental design for a tray or the like, as shown and described.
